HARRY V. GOULD, OF BRIDGEPORT, CONNECTICUT.

PARALLEL CLAMP FOR HOLDING JIG AND FIXTURE BUTTONS.

1,394,004.

Specification of Letters Patent.

Patented Oct. 18, 1921.

Application filed February 3, 1919. Serial No. 274,783.

To all whom it may concern:

Be it known that I, HARRY V. GOULD, a citizen of the United States, residing at Bridgeport, county of Fairfield, State of Connecticut, have invented an Improvement in Parallel Clamps for Holding Jig and Fixture Buttons, of which the following is a specification.

This invention has for its object to provide a clamp especially adapted for use by tool makers in adjusting the tubular buttons, so called, commonly known as jig and fixture buttons and used where it is required to locate holes with extreme accuracy in jigs and fixtures; a valuable feature of the invention being that it provides parallel edges between which a button may be moved in one direction only thus enabling a second adjustment to be made without causing the slightest error in the previous adjustment.

With these and other objects in view I have devised the novel button holding clamp which I will now describe referring to the accompanying drawing forming a part of this specification and using reference characters to indicate the several parts.

Figure 1 is an elevation of my novel holding clamp as in use;

Fig. 2 a perspective view of the clamp and accessory parts; and

Fig. 3 is an elevation partly in vertical section, illustrating different positions of the clamp in laying out holes in a jig, fixture or other piece of work.

10 denotes a jig, fixture or other piece of work, which for convenience I will hereafter refer to as a jig, 11 screws, 12 a jig or fixture button, which for convenience I will term a button, 13 washers and 14 and 15 nuts. Coöoperating with these parts is a clamp or yoke consisting of a cross piece 16 having a central unthreaded hole 17 and arms 18 having at their ends bars 19 lying at right angles to the arms. The bars are 45 provided with inner faces 20 which lie parallel to each other and are preferably provided, for convenience in use, with recesses 21 which receive the button, as will be more fully explained. The faces may be adjusted 50 to the button by means of screws 22 extending between the bars.

Turning now to Fig. 3, suppose that it is required to locate four holes at substantially the positions occupied by the four screws in 55 the figure. Four buttons would be used, which are indicated respectively by 12^a, 12^b,

12^c and 12^d, the latter appearing in dotted lines only, in the upper left hand corner. It will be understood of course that every jig is supposed to have two working edges, 60 constituting a right angle triangle, from which to scale distances and from which a screw 11 may be located. These working edges, in the present instance, are indicated by 23 and 24. The starting point, in the present instance, is the upper right hand corner of the jig, using edge 23 as a horizontal working edge with edge 24 as its perpendicular. The center of a hole for the first screw is located as accurately as possible, in the usual manner, and a drilling point indicated. From this point the other drilling points are scaled off and scribed, and then the four holes are drilled and threaded. Next a screw 11 is turned into each hole, 65 a button placed on each screw, and each button secured in place by a nut 15 and washer, the nuts over buttons 12^b, 12^c and 12^d being turned down tightly enough to hold the buttons frictionally, leaving them however free to be moved by tapping and button 12^a being locked in place. It will be understood of course that the longitudinal holes in the buttons are of appreciably greater diameter than the screws, so that the buttons may have the necessary lateral movement. The 70 exact perpendicular distance between buttons 12^a and 12^b is now obtained by the use of a suitable measuring instrument, for example a height gage, button 12^b being moved 75 upward or downward as may be required by tapping. This is the first perpendicular adjustment of button 12^b. The position of the jig is now changed, making edge 24 the horizontal and edge 23 the perpendicular. Up to this time no use has been made of the 80 present invention, which is, however, of great value in accurately locating buttons 12^b, 12^c and 12^d. A clamp is now placed over button 12^b, use being made of the recesses in 85 passing the bars over the button. The clamp is then moved sufficiently to place the button between the parallel faces of the bars, and permit the screw 11 to pass through 90 hole 17 in the clamp. The bars of the clamp are placed parallel with edge 23 and the clamp is locked in place by a nut 14 and washer. 95

It is now that the advantages of the present invention are to be appreciated in adjusting button 12^b up or down. If it was not for the parallel edges of the bars nothing 100

would prevent button 12^b from moving laterally one way or the other, thereby causing an error in the first perpendicular measurement. When this second perpendicular adjustment of button 12^b is obtained, by the use of a suitable measuring instrument, the button is locked in place by tightening the corresponding nut 15. Nut 14 is now turned off and the clamp removed, leaving button 10 12^b locked by the nut 15 ready for testing.

The operations just described in locating button 12^b are repeated in locating button 12^c and again in locating button 12^d.

Having thus described my invention, I 15 claim:

1. A clamp of the character described comprising a cross piece having a central unthreaded hole, arms extending from the cross piece, and bars having parallel inner 20 faces at the ends of the arms, said bars being provided with recesses for convenience in passing the bars over a fixture button.

2. A clamp for adjusting tool makers' jig and fixture buttons, comprising a cross piece 25 having a central unthreaded hole to receive a screw, fixed arms extending from the cross piece, bars with parallel button engaging faces extending from said arms, and screws extending between the bars by which the 30 parallel button engaging faces may be adjusted toward or from each other.

3. The combination with a screw and a tubular button of greater internal diameter than the screw, of a clamp comprising a 35 cross piece having a central unthreaded hole to receive the screw, arms extending from the cross piece, and bars at the ends of the arms having parallel inner faces adapted to engage the button.

4. The combination with a screw and a 40 tubular button of greater internal diameter than the screw, of a clamp comprising a cross piece having a central unthreaded hole to receive the screw, arms extending from the cross piece, bars at the ends of the arms 45 having parallel inner faces adapted to engage the button, a nut on the screw lying under the cross piece by which the button may be frictionally held or locked, and a nut on the screw above the cross piece by which the clamp is held in place.

5. The combination with a screw and a tubular button of greater internal diameter than the screw, of a clamp comprising a 55 cross piece having a central unthreaded hole to receive the screw, arms extending from the cross piece, bars at the ends of the arms having parallel inner faces adapted to engage the button and recesses to receive the button in attachment, and nuts and washers 60 on the screw above and below the cross piece by which the button and the clamp may be independently held in place.

6. The combination with a screw and a tubular button of greater internal diameter 65 than the screw, of a clamp comprising a cross piece having a central unthreaded hole to receive the screw, arms extending from the cross piece, bars at the ends of the arms having parallel inner faces adapted to 70 engage the button, screws extending between the bars by which the parallel faces may be adjusted relatively to the button, and nuts and washers on the screw above and below the cross piece by which the button and the 75 clamp may be independently held in place.

In testimony whereof I affix my signature.
HARRY V. GOULD.
